FIG. 4.

UNITED STATES PATENT OFFICE.

WENSEL MORAVA, OF CHICAGO, ILLINOIS.

COTTON-CROP CLEANER.

1,409,308.

Specification of Letters Patent. Patented Mar. 14, 1922.

Application filed August 14, 1920. Serial No. 403,523.

To all whom it may concern:

Be it known that I, WENSEL MORAVA, a citizen of the United States, and a resident of the city of Chicago, in the county of 5 Cook and the State of Illinois, have invented certain new and useful Improvements in Cotton-Crop Cleaners, of which the following is a specification, reference being had to the accompanying drawings, forming a 10 part thereof.

The purpose of this invention is to provide an improved apparatus for the purpose of cleaning a harvested cotton crop by separating from the fiber the hulls and refuse 15 which are necessarily gathered with the fiber. It consists in the elements and features of construction shown and described, as indicated in the claims.

In the drawings:

20 Figure 1 is a side elevation of an apparatus embodying this invention.

Figure 2 is a plan view of the same.

Figure 3 is a detail section at the line 3—3, on Figure 1.

25 Figure 4 is a section at the line, 4—4, on Figure 3.

The apparatus shown in the drawings comprises an endless conveyer, made of woven wire, perforated metal or other reticulated or perforated flexible material, 30 adapted for forming the endless belt of a conveyer, onto which at the entering end of the path of travel of its upper carrying ply, the material to be operated upon is delivered.

35 Overhanging the middle portion of the length of the path of travel of the operating ply there is a card-armoured endless belt whose lower ply travels near enough to the upper ply of the conveyer belt so that the

40 cards of the card-armoured belt may engage the fiber of the material carried by the latter, picking it up and carrying it around with said card-armoured belt to a point in the return course of the latter at which it

45 is overhung by a rotary brush or card combining cylinder, which takes the fibrous material from the card-armoured belt and delivers it to a hopper or conveyer, a combing device or the like being employed if necessary to strip the fiber from said rotary brush or combing cylinder.

50 For insuring the engagement of the fibrous material by the cards of the card-armoured belt, the latter is perforated and the chamber which is bounded on four sides by the two plies of the card-armoured belt and the two drums

on which said belt is carried, is closed at the other two sides by casing-heads through one of which an air conduit is connected with the chamber, the conduit being connected with a source of suction as the intake of a rotary fan or blower, for producing partial vacuum in and suction through the chamber, causing the air to flow up through the perforations of the card-armoured belt, 65 and through the perforations of the conveyer belt below the same, lifting the fiber against the card-armoured belt so as to insure its being engaged thereby, the discharge of the fan or blower being connected 70 for delivering an air blast up through the conveyer belt against the material thereon, to drive it against the overhanging cards, while another branch of the fan discharge directs an air blast between the two belts in 75 the reverse of the direction of inclination and projection of the card teeth to drive the material into engagement with said teeth. At the end of the path of travel of the lower ply of the card-armoured belt 80 where the belt passes up around the idle drum, there is located a flexible-winged rotor whose flexible wings constitute bats revolving near enough to the arc of the card-armoured belt as it passes up around the 85 drum to bat off the hulls and other refuse material which may be adhering to the fiber, the refuse falling upon the conveyer belt below and being conducted with the refuse already remaining on that belt to the discharge side thereof, where a suitable receptacle receives it.

In the drawing, 1 is the endless conveyor belt carried around a driving drum, 2, and idle drum, 3, whose shafts, 4 and 5, respectively are journaled in a suitable frame structure, A. 6 is the power pulley on the driving shaft, 4, of the driving drum, 2. 7 is a chute by which the material to be treated is delivered upon the entering end of the upper ply of the conveyor belt, 1. This conveyor belt, as above mentioned, is made of perforated material and may be either woven wire fabric or any other suitable flexible perforated or reticulated material. 100 8 is the card-armoured belt, which carries a multiplicity of longitudinal strips of card, 8^a, slightly spaced apart, the intervals of the belt between the card being perforated as seen at 8^b. The cards are mounted with 105 their inclined teeth or brush wires projecting forwardly in the direction of travel of the

belt, for engaging the fibrous material. 9 is the driving drum and 10 the idler drum of the card-armoured belt having shafts, 9^a and 10^a, respectively, suitably journaled in the frame, the shaft, 9^a, having a driven pulley, 11, for the main drive belt hereinafter mentioned. 12 is the rotary brush or card-combing cylinder having a shaft, 13, journaled in the frame and carrying the pulley, 14, by which the said cylinder is rotated for combing or brushing the fibrous material from the card-armoured belt, 8, and delivering into the receiving hopper, 26. 15, 15, are the heads which complete the closure of the chamber which is otherwise enclosed by the two plies of the card-carrying belt and the drums on which that belt is carried. 16 is the suction air conduit leading to the intake of a fan, 20, and opening through one of said heads, 15. 21 is the discharge conduit from the fan. It leads to a casing, 22, under the upper ply of the conveyor belt, extending substantially under the whole length of the lower ply of the card-armoured belt, 25 and open upwardly over its whole extent. This casing has a branch, 23, affording a discharge at 24, between the conveyor belt and the card-armoured belt, for delivering an air blast longitudinally of said belts for driving the fibrous material on the conveyor belt in the opposite direction to that of the travel of the card-armoured belt, and thereby opposite to the direction of projection of the teeth or brush wires of the card. 35 17 is the shaft of the hull-and-refuse-separating batting device, being a flexible winged rotor whose flexible wings or bats are seen at 18. 19 is a pulley on the shaft of the batting device by which it is rotated. 28 40 represents a chute-board for directing the discharged hulls into a receptacle not shown. For driving all the several elements of this apparatus by a single driving belt, the pulleys, 6, 11, 14 and 19, are mounted on 45 their respective shafts in the same vertical plane or zone, and in said plane or zone is a drive pulley, 30, on a power shaft, 31, at the opposite end of the system from that at which the driving pulley of the endless conveyor, 1, is situated; and driving belt, 35, encompasses said pulleys from the driving pulley, 31, by way of the pulleys, 6, 19, 14 and 11, in the order named, the path of said belt making re-entrant loops for and passing 50 around the pulleys, 19 and 11, for driving said two pulleys in the opposite direction from the remainder of the system, as it will be seen is necessary in order that the bats, 18, may attack the hulls and refuse by movement in the opposite direction from that which they are for the time being carried by the card-armoured belt, and that the lower ply of said card-armoured belt, may have the same direction of travel as the upper ply of the conveyor belt, and may move 55 60 65

in the opposite direction from the direction of rotation of the rotary brush or card-combing cylinder, 12, at the point at which the latter is designed to take the fiber from said card-armoured belt as described. 70

It will be understood that the purpose of giving the card-armoured belt higher speed than the conveyor belt, is that said belts traveling in the same direction at the proximate plies, the difference in the rate of movement in the direction in which the teeth of the card are inclined, shall be in favor of the card-armoured belt; that is, that the card armoured belt shall have a movement relative to the material on the conveyor belt 75 forward in direction of projection of the card teeth or brush wires, to cause these teeth to engage said material, and for this purpose the difference in speed between the two belts to be considered is the algebraic difference, consisting of the airthmetical difference when the two belts travel in the same direction, and of the arithmetical sum when they travel in opposite directions. For certain reasons of convenience of construction, 80 it has been preferred to give the two belts the same direction of travel at their proximate plies and therefore to give the belt, 8, the higher speed; but it will be understood that this is not obligatory. 85 90 95

I claim:

1. An apparatus for the purpose indicated, comprising in combination, an endless belt conveyer; a second endless belt armed with cards overhanging the conveyer 100 belt at an intermediate part of the carrying ply of the latter; means for driving said belts to give their proximate plies movement in the same direction and for giving the card-armoured belt a higher speed than the conveyer belt for causing the cards of the card-armoured belt to engage with the material on the conveyer belt; and a rotary brush or card-combing cylinder articulated with the card-armoured belt in its return course from 105 the conveyer belt. 110

2. An apparatus for the purpose indicated, comprising in combination, an endless belt conveyer; a second endless belt armed with cards overhanging the conveyer 115 belt at an intermediate part of the carrying ply of the latter; means for driving said belts to give their proximate plies relative movement for causing the cards of the card-armoured belt to engage with the material on the conveyer belt, the conveyer belt being perforated for admitting an air blast through the upper ply of said belt for driving the material thereon up against the overhanging ply of the card-armoured belt 120 and means, for clearing from the card-armoured belt the material gathered thereby in the return course of said card-armoured belt from the conveyor belt. 125

3. An apparatus for the purpose indi- 130

- cated, comprising, in combination, an endless belt conveyer; a second endless belt armed with cards overhanging the conveyer belt at an intermediate part of the carrying ply of the latter; means for driving said belts to give their proximate plies relative movement for causing the cards of the card-armoured belt to engage with the material on the conveyer belt; means for producing 10 and directing an air blast longitudinally of said belts into the interval between their proximate plies in the direction opposite to the travel of said ply of the card-armoured belt, for driving the material carried by the 15 conveyer belt into engagement with the card teeth or brush wires, and means for clearing the material so gathered from the card-armoured belt in its return course from the conveyer belt.
- 20 4. An apparatus for the purpose indicated comprising in combination, an endless belt conveyer; a second endless belt armed with cards overhanging the conveyer belt at an intermediate part of the carrying ply of the 25 latter; means for driving said belts to give their proximate plies relative movement for causing the cards of the card-armoured belt to engage with the material on the conveyer belt; the conveyer belt being perforated 30 throughout its length, the card-armoured belt being perforated between the cards thereof; heads closing at the remaining sides the space enclosed at four sides by the two plies of the card-armoured belt and the drums on 35 which the latter is carried, and an exhaust conduit connected with one of said heads.
5. An apparatus for the purpose indicated comprising in combination, an endless belt conveyer; a second endless belt armed with
- cards overhanging the conveyer belt at an 40 intermediate part of the carrying ply of the latter; means for driving said belts to give their proximate plies relative movement for causing the cards of the card-armoured belt to engage with the material on the conveyer belt; means for clearing the material gathered from the card-armoured belt therefrom in its return course from the conveyer belt; a flexible-winged rotating wiper mounted parallel to the card-armoured belt drums 45 adjacent to said belt at its upward course around the drums about which it turns in departing from the conveyer belt, and means giving the wiper the same direction of rotation as the drums of the card-armoured belt; 50 whereby the wiper wings at the side toward the card-armoured belt move in the opposite direction from the cards passing up around the drum, for battoning off the hulls and refuse carried by the fiber on the cards. 55
6. In the organization defined in claim 1 foregoing, a power shaft parallel to the endless belt drum situated at one end of the conveyer belt; a pulley thereon; a pulley on the corresponding end of the shaft of the 60 remotely situated conveyer belt drum; a pulley on the shaft of the card-combing cylinder; a pulley on the shaft of one of the drums of the card-armoured belt, and the main driving belt traversing said pulleys in 65 the order named having a re-entrance loop for passing around the last mentioned pulley to drive it in the opposite direction from the other pulleys of the system. 70

In testimony whereof, I have hereunto set 75
my hand this 9th day of August, at Chi-
cago, Illinois.

WENSEL MORAVA.
